UNITED STATES PATENT OFFICE.

TALBOT C. DEXTER, OF PEARL RIVER, NEW YORK.

PAPER-FEEDING MACHINE.

No. 886,117.

Specification of Letters Patent.

Patented April 28, 1908.

Application filed August 1, 1907. Serial No. 386,602.

To all whom it may concern:

Be it known that I, TALBOT C. DEXTER, a citizen of the United States, and a resident of Pearl River, in the county of Rockland and State of New York, have invented certain new and useful Improvements in Paper-Feeding Machines, of which the following is a specification.

My present invention relates generally to improvements in paper feeding machines, and particularly to feeding machines of the sheet combing type, in which the pile of sheets is acted upon by combing feeding devices which comb or feather out the top sheets of the pile to gradually separate the successive sheets near the top so they may be drawn from the pile periodically and fed to any machine arranged to operate upon the individual sheets. Machines of this type are set forth in Letters Patent No. 829,854, granted to me August 28th, 1906, and No. 850,821, granted April 16th, 1907, and my present invention may best be considered in the light of an improvement upon the mechanisms for raising and lowering the sheet combing devices and the sheet actuated controlling devices in machines such as covered by the said patents.

The purpose of my present invention is to produce a simple and sensitive sheet actuated tripping mechanism for controlling the operation of the sheet moving instruments in a paper feeding machine.

The present improvements are especially valuable as part of a feeding machine of the type shown in my above named patents, but they are also applicable to other forms of feeding machines, and I would have it understood at the outset that I do not intend to limit my invention to its application to the particular type of machine which I have adopted for the purpose of illustration in this application.

Broadly considered, my invention consists, in combination with a sheet moving instrument and means for raising and lowering the instrument with reference to a pile of sheets, of a movable member controlling the elevating means for the sheet moving instrument, and a sheet actuated blade or plate adapted to be thrown into engagement with said controlling member by the action of the sheet for tripping the controlling member and permitting or causing the elevating means to operate.

In carrying my invention into practical

use in the type of machine shown in my above named patents, I have provided a paper feeding machine with two independently acting sheet moving devices (preferably sheet combing wheels), an independent spring device for raising each combing wheel out of contact with the pile of sheets, suitable cam mechanism for lowering the combing wheels into active relation with the pile of sheets, an independent latching device for restraining each spring device when the combing wheels are operating, a rock arm projecting from each latching device and supporting an antifriction wheel or roller in operative relation to a constantly driven roller, and an independent tripping finger supported in the path of the sheets and carrying a blade or plate which is presented adjacent to said coöperating wheels or rollers, and is adapted to be moved by a sheet into the bite of said rollers to be carried thereby between the rollers to separate them and cause the rock arm to rock for releasing the latching device.

I prefer to arrange twin rollers above and below the plane of the sheet adjacent to the sheet-actuated tripping finger so as to firmly support the advancing edge of the sheet when it engages and actuates the tripping finger. The upper twin rollers are preferably arranged in the form of drop rollers under the control of mechanism which is actuated by the elevating means of the main sheet moving instrument so that said upper twin rollers will maintain their feeding relation with the advancing sheet only while the main feeding instrument is operating. These rollers not only assist in the final registering movement of the sheet, but they maintain the sheet in proper position for the engagement of the main drop rollers which feed the sheet from the pile.

In addition to the sheet control of the tripping blade or plate, I provide a cam operated mechanism for periodically actuating said tripping blade or plate, in the event of the failure of the sheet to operate the same, and also for the purpose of raising the tripping finger out of the path of the sheets to allow the sheets to pass off without interference therefrom, and to reset the tripping fingers in readiness for another sheet after a sheet has completely left the feeding machine.

In order that my invention may be fully understood, I will first describe the same with reference to the accompanying draw-

ings, and afterwards point out the novelty more particularly in the annexed claims.

Figure 1 is a detail vertical transverse sectional elevation of one half of a paper feeding machine embodying my invention, the other half of the machine being omitted. Fig. 2 is a top plan view of the same. Fig. 3 is a vertical longitudinal sectional view of the same, taken on the line *a—a* of Figs. 1 and 2, looking in the direction indicated by the arrows *a, a*. Fig. 4 is a similar view taken on the line *b—b* of Figs. 1 and 2, looking in the direction indicated by the arrows *b, b*. Fig. 5 is a detail vertical longitudinal sectional view, on a larger scale, taken on the line *c—c* of Figs. 1 and 2 and looking in the direction indicated by arrows *c, c*, showing the main parts in tripped position, and omitting some parts for clearness.

Sheet feeding machines of the type to which my present invention relates are provided with two sets of sheet moving devices arranged to operate at opposite sides of the machine. In the accompanying drawings, I have shown only one-half of the machine, including only one of these sheet moving devices, but it will be understood that two such devices of the same construction are employed, each being independently controlled by a sheet actuated tripping device, as hereinafter explained.

The frame-work of my improved machine may be of any suitable construction to properly support the working parts hereinafter referred to.

In the drawings, 1 represents one of the vertical side frames. The side frames are suitably braced to make them rigid by means of stay rods 2, 3, and other frame parts not shown, and within the frame is provided a suitable table or support (not shown) for carrying a pile of sheets, indicated by the reference letter *P*. At the front of the pile of sheets, I provide a series of vertical guide rods or strips, (not shown) for confining the pile.

5 is a constantly driven shaft bearing the lower feed rollers 6 and 7, said shaft 5 being braced at intervals by suitable bearing brackets, (not shown). 8 are drop rollers journaled in the rock arms 9, mounted upon the transverse rock shaft 10. The drop rollers 8 are supported above two or more of the under feed rollers 6, with which they coöperate. The rock shaft 10 extends transversely of the machine, above the constantly running lower shaft 5, and is suitably braced between its ends by two or more bracket arms, not shown, rigidly secured to the auxiliary longitudinal frame pieces 12. The rock shaft 10 is operated by any of the usual forms of mechanism, such, for instance, as shown in my above-named patents, whereby the drop rollers 8 are periodically lowered and raised into and out of engagement with the coöper-

ating under rollers 6, for performing their function of feeding off the successive sheets.

The main cam shaft 20 extends transversely of the machine and is suitably journaled in the main side frames 1 and the auxiliary longitudinal frame pieces 12. This shaft 20 is provided with a driving pulley 25, as shown, or it may be driven in any other suitable manner, said shaft being the shaft from which all other parts of the machine are driven.

The cam shaft 20 carries a large gear 26, which meshes with a smaller gear (not shown) secured to a larger gear 28, journaled upon a stud 29, projecting from the side frame of the machine. The gear 28 meshes with and drives a small intermediate gear (not shown) which in turn drives a small gear 32 keyed to the projecting end of the comber driving shaft 35, hereinafter referred to, and another smaller gear (not shown) keyed to the projecting end of the constantly rotating feed shaft 5 above referred to. This gearing is clearly shown and described in my above named patents.

40 is one of a pair of combing wheels. Each of these combing wheels is freely journaled at 41 upon a rock arm 42, which is freely journaled upon a sleeve 50 which is in turn journaled upon the shaft 35. This shaft 35 has keyed to it a gear 45 which meshes with a gear 46 secured to the combing wheel 40, by which the combing wheel is constantly rotated.

Projecting from one face of the comber-supporting rock-arm is an integral lug 43 in which is mounted an adjustable tappet screw 44. Secured upon the sleeve 50 to one side of the rock arm 42 is a rock arm 51 which is provided with a finger 52, which projects beneath the tappet screw 44 just referred to, and by its engagement therewith lifts the combing wheel away from the pile. By adjusting the screw 44, the limits of rise and fall of the combing wheel can be fixed.

The rock arm 51 is moved in one direction for lifting the combing wheel by a spring mechanism which is normally restrained by a latching device which is periodically released by the sheet actuated tripping device hereinafter explained. The rock arm 51 is moved in the opposite direction to allow the combing wheel to move by gravity into engagement with the pile of sheets by the action of a cam as will now be explained.

Sleeve 50 has at its end, adjacent to the rock arm 51, another rock arm 55 to which is pivotally connected a pitman 56, formed with a yoke-shaped upper end, which straddles the shaft 20. The shaft 20 carries a peripheral cam 58, which engages an anti-friction roller 57 journaled upon the pitman 56, whereby the rock arm 55, sleeve 50, and finger 52 are moved once in each revolution of the shaft 20 to reset the spring and latch-

ing mechanisms (hereinafter described) and allow the combing wheel to rest upon the pile.

The rock arm 51 projects forwardly from 5 the sleeve 50 and has pivotally connected to its forward end a latching bar 60 extending vertically and riding, in its upper end, in a socket formed in a bracket 62 extending laterally from one of the central auxiliary 10 frames 12. Freely journaled upon a pin or bolt 65 projecting laterally from the latching bar 60 is an antifriction roller 64, which normally engages the upper end of a latching arm 63 freely journaled upon a bolt 66 15 mounted in bracket 67 which is secured to one of the frame pieces 12. When the latching arm 63 is in engagement with the antifriction roller 64, said arm will be in proper position to maintain the downward thrust 20 of the latching bar to withstand the pressure of the spring device (presently to be referred to), with the result that the combing wheel will be allowed to rest in its lower operating position. The latching arm 63 is moved 25 into and out of active position during the operation of the machine by the means hereinafter described, its movement out of action being normally under the control of the sheets fed from the pile.

30 A rod 70 is pivoted at 71 to the rock arm 51 and projected therefrom vertically through the guide bracket 62. Surrounding the rod 70 and confined between a collar 70^a above the rock arm 51 and the guide bracket 62 is 35 an expansion spring 75 which tends to throw down the arm 51 and move up the finger 52 for raising the comber away from the pile of sheets. This spring tendency is normally restrained by the latching arm 63, and the 40 latching bar 60.

Turning now to the sheet controlled tripping mechanism for releasing the comber elevating means, it will be observed that a short shaft 80, freely journaled in a forward 45 extension of the bracket 67, carries the rubber faced roller 81 and a relatively large gear wheel 82, said roller 81 and gear 82 being rigidly secured upon the shaft 80 so as to revolve therewith. The gear 82 meshes with 50 one of the train of gears 83, 84 and 85, the intermediate gears 83 and 84 of which train are freely journaled at 86 and 87 upon the bracket 67, while the driving gear 85 of said train is keyed to the comber operating 55 shaft 35. By this mechanism the roller 81 is caused to travel constantly in the direction indicated by the arrow in Fig. 5 of the drawings. Freely journaled upon the bolt 66 which supports the tripping arm 63 is a rock 60 arm 90 projecting forwardly and carrying in its forward end a freely journaled rubber faced roller 91 which is supported directly above the constantly running lower roller 81, and, in the normal operative position of the 65 machine, runs in peripheral contact with

and is driven by said roller 81. The forwardly projecting rock arm 90 is formed integral with or rigidly secured to a tubular hub 92 which journals upon the bolt 66, and is formed at one end with the upwardly projecting arm 93 formed with the laterally projecting fingers 94 which project in front and rear of the tripping arm 63. The arm 93 is formed with a horizontal slot 95 through which passes an adjusting set screw 96 which is threaded into a suitable opening formed in the trip arm 63. The purpose of the slot 95 and set screw 96 is to adjust the relation of tripping arm 63 and roller rock arm 90 so as to accurately present the tripping arm 70 75 80 85 90 95 100 105 110 115 120 125 the roller 81 being designed to frictionally engage the under surface of the blade 106, when it is moved into contact therewith, for the purpose of causing said blade to pass 5 over the roller 81 and under the roller 91 for elevating roller 91 and rock shaft 90 for tripping the arm 63. It will be understood that this action takes place when the leading edge of a sheet moving from the pile engages 10 the tripping finger and moves the blade or plate 106 into the bite of the rollers 81 and 91.

110 is a rock arm freely journaled upon the bolt 103 along side of the hub 101 of the tripping finger. This rock arm has formed 15 integral with and projecting up from its hub portion, a short rock arm 111 formed with laterally projecting fingers 112, which are presented in front and rear of the upwardly projecting arm 105 which carries the plate or 20 blade 106. These fingers 112 serve to confine the tripping finger 100 and arm 105, and to cause them to operate under the action of the cam under certain conditions which will be hereinafter explained. A rod or pitman 25 113 is pivoted at 114 to the rock arm 110 and extends upwardly therefrom and has its upper end pivoted at 115 to the forward end of a rock arm 116 journaled at 117, and carrying adjacent to its end a freely journaled 30 antifriction roller 118 which runs in peripheral contact with controlling cam 119 keyed to the main cam shaft 20. The cam 119 has a main high portion 119^a for about one-half of its circumference, a low portion 119^b for 35 about one quarter of its circumference, and an intermediate low portion 119^c for the remaining one quarter of its circumference. The cam travels in the direction indicated by the arrow in Fig. 5 of the drawings. 40 While the antifriction roller 118 is in contact with the high portion 119^a of the cam, the tripping finger 100 will be elevated above the path of the sheets to allow the free passage of a registered sheet from the feeding machine. When the roller 118 passes from the 45 high portion 119^a of the cam to the extreme low portion 119^b, the tripping finger and controlling blade or plate are returned to starting position, the tripping finger being moved 50 into the path of the sheets, and the blade or plate being passed between the rollers 81 and 91 to its position in front of said rollers. When the roller 118 is on the intermediate portion 119^c of the cam, the tripping finger 55 is in tripping position, the rear finger 112 of rock arm 111 having been moved back out of engagement with arm 105 by the lift of roller 118 from the lower portion 119^b to intermediate portion 119^c of the controlling cam. 60 In this movement from the low portion to the intermediate portion of the controlling cam, the trip finger 100 and blade carrying arm 105 are not moved, but the described action of the controlling rock arm 111 is necessary 65 to shift the rear finger 112 away from arm

105 to free the tripping finger preparatory to the automatic tripping action of the sheet.

As described above the lower constantly running shaft is provided with the ordinary under-feed rollers 6 and the special under-feed rollers 7. These rollers 7, two of which are provided in the machine, are in the form of twin rollers, with an annular groove or recess 7^a separating the two parts. The same result can, of course, be accomplished 75 by mounting two separate rollers upon the shaft 5 with a sufficient space between them. The twin rollers 7 are mounted upon the shaft 5 directly beneath the tripping fingers 100 so that the lower sheet engaging portion 80 100^a of each tripping finger will project into the annular groove or recess 7^a of the under twin rollers. This is clearly shown in Fig. 1 of the drawings.

Coöperating with the under twin rollers 7 are 85 the auxiliary drop rollers 125 which are also arranged as twin rollers or as pairs of independent rollers. These drop rollers 125 are freely journaled at 126 upon the forward ends of rock arms 127 pivoted at 128 upon 90 the downwardly projecting bracket arms 129 extending below the comber operating shaft 35 and supported from one of the main brackets which is mounted upon one of the central frame pieces 12. Projecting rearwardly from each rock arm 127 is a finger 130 carrying a laterally projecting pin or lug 131 which is pivotally connected at 132 to the lower end of a rod or pitman 133 which is pivotally connected at its upper end 134 with a rock arm 135 mounted upon a rock 95 shaft 136 which passes through and is freely journaled upon suitable bearings in the main bracket 67 and an auxiliary bracket 137 secured thereto. The rock shaft 136 has secured to its opposite end a rock arm 138 to the free end of which at 139 is pivoted a downwardly projecting link 140 which is pivotally connected at its lower end with the rock shaft 51 by which the combing wheel is raised and 100 lowered. From this arrangement it will be observed that when one of the combing wheels is raised away from the pile of sheets, the coöperating auxiliary twin drop rollers 125 will also be raised, and when the said 105 combing wheel is lowered into operative engagement with the pile, said twin drop rollers 125 will be lowered into engagement with under twin rollers 7. It will of course, be understood that the arrangement and proportions of the rock shaft, rock arms and links, controlling drop rollers 125 are such as to properly harmonize their action with the rest of the machine. This action will be more fully explained in connection with the 110 operation of the machine.

It will be observed particularly with reference to Fig. 1 of the drawings that the leading edge of the sheet which engages and actuates the tripping fingers 100 is firmly 115 120 125 130 135 140

supported above and below upon both sides of each tripping finger and is positively fed by the under twin rollers 7 and the upper twin drop rollers 125. This provides a very effective gaging edge for actuating the tripping fingers.

Extending longitudinally of the machine, at each side is a rock shaft 155 journaled in bracket arms 156 extending down from the auxiliary frame pieces 12. At the forward end of each of these rock shafts is a rock arm 157 carrying at its upper end an antifriction roller 158, which operates in engagement with a face cam 159, keyed to the cam shaft 20. Each of the rock shafts 155 carries a horizontal rock arm which is adjustable longitudinally of the machine, and carries a weighted tail gripper 160 of the same construction as fully set forth in my above named patents.

The following brief explanation will make clear the operation of my improved machine: It being understood that a machine embodying my improvements is provided with two sets of sheet combing mechanisms, each independently controlled by a sheet actuated tripping device as described, the machine is started in operation and the combing wheels lowered upon the top of the pile of sheets, the combing wheels being driven through the gears as above explained. In this normal operative position of the machine, the spring elevating mechanisms for the combers are held out of action by the latching arms 63 and latching bars 60, the rollers 91 being in peripheral contact with and driven by the constantly running rollers 81, and the tripping fingers 100 with their controller blades or plates 106 being in normal position as shown in Fig. 4 of the drawings. In this starting position of the machine, the main drop rollers 8 are elevated away from the ordinary under feed rollers 6, and the auxiliary twin drop rollers 125 are running in peripheral contact with the under twin rollers 7. The tail grippers 160 are held out of contact with the pile. It will be observed from the relative position of cams 58 and 119 in Fig. 4 of the drawings that coincidental with the lowering of the 50 combing wheels into operative engagement with the pile of sheets, the intermediate portions 119^a of cams 119 come into engagement with the antifriction rollers 118 for relieving the arms 105 of the tripping fingers from the 55 engagement of the rear fingers 112 of rock arms 111, so that when the combing wheels start to act on the sheets, the tripping fingers are free to move under the action of the leading edge of the sheet which is being separated 60 and fed forward from the pile. The two combing wheels will continue to operate until the forward edge of the top sheet in front of one of the combing wheels is moved forward sufficiently to engage and actuate one of the 65 tripping fingers 100. In a combing machine,

in which a number of the sheets at the top of the pile are gradually separated and shifted forwardly, the combing wheels operate but a moment to shift the top sheet into registered position. The instant that the sheet engages one of the tripping fingers, the actuated tripping finger will cause the plate or blade 106 connected therewith to enter between the rotating rollers 81 and 91, with the result that the roller 91 will be raised sufficiently to cause latching arm 63 to be moved from beneath the roller 64 of one of the latching bars 60, which frees the spring device and permits it to instantly act upon the rock arm 51 for elevating the combing wheel away from the pile of sheets and arrests the action of the particular combing wheel upon the sheets. This action is immediately followed by the same operation on the other combing wheel, as the edge of the sheet in front of such other combing wheel reaches registered position and actuates the other tripping finger. When both combing wheels have been arrested by these independent sheet actuated tripping devices, the sheet will be found to be in registered position in readiness for the operation of the delivery drop roller mechanism, which comes into play to feed the registered sheet from the pile of the feeding machine and deliver it to the printing press folding machine or other machine which is to operate upon the sheets.

In the normal operation of the feeding machine, it will be found that both combing wheels are thrown out of operation at approximately the same time, there usually being but slight variations in the position of the sheets upon the pile. As stated above, the auxiliary twin drop rollers 125 release their hold upon the registered edge of the sheets the same instant that the combing rollers release their engagement with the sheets. In addition to the advantage of firmly presenting the leading edge of the sheet against the tripping fingers, this arrangement is desirable as providing means for maintaining positive hold upon the sheets up to the moment of engagement of the main delivery drop rollers. As the successive sheets are engaged and fed off by the delivery drop roller mechanism, the tail grippers 160 engage the under sheet of the pile just back of the rear edge of the top sheet for holding the pile in place. Coincident with the operation of the delivery drop roller mechanism, the high portions 119^a of controlling cams 119 engage the antifriction rollers 118 upon rock arms 116 and actuate the rock arms 111 for causing the forward fingers 112 to positively engage the arms 105 for moving the wedge blades or plates 106 rearwardly and the tripping fingers 100 forwardly to place the tripping fingers out of the path of the sheet being delivered. This position of the parts is shown in Fig. 5 of the

drawings. The parts of the machine remain in this position until the sheet has entirely passed beyond the tripping fingers, when by the arrival of the extreme low portions 119^b of the cams 119 beneath the anti-friction rollers 118, the tripping fingers are returned positively to their operative positions in the path of the sheets, and by the same movement the blades or plates 106 are returned to normal position in front of the rollers 81 and 91. At the same time that the tripping fingers and allied parts are returned to their normal positions, the cams 58 forcibly rock the sleeves 50 to permit the combing wheels 40 to again fall into operative engagement with the top of the pile of sheets, which action at the same time compresses the springs 75 and resets the latching mechanisms, the latching arm 63 moving back beneath the antifriction roller 64, and the rollers 91 dropping back into peripheral engagement with the rollers 81. Simultaneously with the falling of the combers 40, auxiliary twin drop rollers 125 are again permitted to fall into peripheral engagement with the twin under feed rollers 7. The described operation is then repeated for the next sheet of the pile.

It will be understood that the provision of lost motion between the controlling rock arm 111 and the arm 105 of the tripping device is for the purpose of providing means for positively actuating the tripping device once every revolution of the cam shaft 20 to move the tripping finger 100 out of the path of the sheets, and to reset this part of the mechanism after a sheet has been fed off, and at the same time allow for freedom of motion of the tripping device under the action of a sheet independently of the cam actuated controlling mechanism.

So as to maintain the proper timing of the feeding mechanism with the delivery drop roller mechanism, the controlling cams 119 will once in every revolution of the shaft 20, cause the tripping devices to operate for actuating the latching devices. If this were not done, it will be clear that the sheet would be delivered to the tripping fingers at a time when the tripping fingers could not operate because the coöperating parts of the mechanism would not be in proper position, and even if this did not happen, there would be constant danger of delivering sheets to the delivery drop roller mechanism at improper times.

While I have illustrated and described my invention as applied to a feeding machine of the sheet combing type, I would have it understood that I do not intend to limit the scope of my invention to this application, but consider my invention sufficiently broad and novel to include its application to any form of paper feeding machine in which the active operation of a sheet moving instru-

ment of any construction is controlled by the position of the sheet acted upon through some suitable form of tripping device involving the principle above set forth.

What I claim is:

1. In a paper feeding machine, the combination of a sheet moving instrument, automatic means for arresting the operation of said instrument, a movable member normally restraining said instrument-arresting means, and a sheet-actuated wedging blade or plate adapted to move into engagement with and thereby actuate said movable restraining member and release the arresting means. 70

2. In a paper feeding machine, the combination of a sheet moving instrument, means for operating said instrument, means for raising the said instrument into inactive position, a movable member normally restraining said instrument raising means, and a sheet actuated wedging blade or plate adapted to move into engagement with and thereby actuate said movable restraining member to release and permit the operation of the instrument raising means. 80

3. In a paper feeding machine, the combination of a sheet moving instrument, means for operating said instrument, means for raising the said instrument into inactive position, a movable member normally restraining said instrument raising means, a wedging blade or plate adapted to move into engagement and thereby actuate said movable restraining member, and a tripping finger supported in the path of sheets and suitably connected with said wedging blade or plate to actuate it. 90

4. In a paper feeding machine, the combination of a sheet moving instrument, automatic means for arresting the operation of said instrument, a movable member controlling and normally restraining said instrument arresting means, a fixed member adjacent to said movable member, and a sheet-actuated wedging blade or plate adapted to be projected between said movable controlling member and said fixed member to thereby operate the former and release the arresting means. 105

5. In a paper feeding machine, the combination of a sheet moving instrument, automatic means for arresting the operation of said instrument, a movable member controlling said arresting means, an antifriction roller upon said movable member, and a sheet-actuated wedging blade or plate adapted to move into engagement with said roller and thereby operate said controlling member to release said arresting means. 110

6. In a paper feeding machine, the combination of a sheet moving instrument, automatic means for arresting the operation of said instrument, a movable member controlling said arresting means, an antifriction roller upon said movable member, a coöper- 125

- ating roller journaled upon a fixed bearing adjacent to said movable controlling member, and a sheet-actuated wedging blade or plate adapted to be projected between said 5 rollers and thereby operate said movable member and release said arresting means.
7. In a paper feeding machine, the combination of a sheet moving instrument, means for operating said instrument, means for 10 raising and lowering the said instrument, a movable member controlling the operation of said instrument raising means, a fixed member adjacent to the movable member, a wedging blade or plate adapted to be projected 15 between said movable member and said fixed member, for operating the former, and a tripping finger supported in the path of sheets and suitably connected with said blade or plate.
- 20 8. In a paper feeding machine, the combination of a sheet moving instrument, means for operating said instrument, means for raising and lowering the said instrument into and out of operation, a movable member controlling said raising means, a fixed member adjacent to said movable member, coöperating rollers journaled upon the movable and fixed members, and a sheet-actuated 25 wedging blade or plate adapted to be projected between said rollers for operating said movable member and permitting the instrument raising means to operate.
9. The combination of a sheet moving instrument, means for operating said instrument, means for arresting the operation of 30 said instrument, means normally restraining said arresting means, and a sheet actuated wedging blade or plate adapted to move into engagement with and thereby actuate 35 said restraining means to permit the arresting means to operate.
10. The combination of a sheet moving instrument, means for operating said instrument, means for arresting the operation of 40 said instrument, means normally restraining said arresting means, a pair of rollers operating in peripheral contact, a movable support for one of said rollers arranged to actuate 45 said restraining means, and a sheet-actuated wedging blade or plate adapted to be interposed 50 between said rollers and thereby actuate said movable support.
11. The combination of a sheet moving instrument, means for operating said instrument, means for arresting the operation of 55 said instrument, including a latching bar and a coöperating latching arm, a rock arm connected with the latching arm, an anti-friction roller journaled upon said rock-arm, 60 and a sheet actuated blade or plate adapted to engage said antifriction roller and thereby disengage the latching arm from the latching bar.
12. The combination of a sheet moving instrument, means for operating said instru- 65
- ment, means for arresting the operation of said instrument, including a latching bar and a coöperating latching arm, a roller journaled upon a fixed bearing, a rock arm projecting from the latching arm, an anti-friction roller journaled upon said rock arm and supported thereby in peripheral contact with said fixed roller, and a sheet actuated wedging plate or blade adapted to be projected between said rollers and thereby disengage the latching arm from the latching bar. 70
13. In a paper feeding machine, the combination of a sheet moving instrument, means for operating the sheet moving instrument, a pair of coöperating rollers, one of which is mounted on a stationary support, and the other of which is mounted on a movable support, a sheet actuated wedging blade or plate adapted to be interposed between said rollers for separating them, and means actuated by the separation of said rollers for arresting the operation of the sheet moving instrument. 75
14. In a paper feeding machine, the combination of a sheet moving instrument, means for operating the sheet moving instrument, a pair of coöperating rollers, one of which is mounted on a stationary support, and the other of which is mounted on a movable support, means for driving the roller on the stationary support, a sheet-actuated wedging blade or plate adapted to be interposed between said rollers for separating them, and means actuated by the separation of said rollers for arresting the operation of the sheet moving instrument. 80
15. In a paper feeding machine, the combination of a sheet moving instrument, a rotary shaft for operating the sheet moving instrument, a pair of peripherally engaging rollers, one of which is mounted on a stationary support, and the other of which is mounted on a movable support, gearing between said shaft and the roller upon the stationary support, a sheet actuated wedging blade or plate adapted to be interposed between said rollers for separating them, and means actuated by the separation of said rollers for arresting the operation of the sheet moving instrument. 85
16. The combination, in a paper feeding machine, of a sheet moving instrument, means for operating said instrument, a sheet actuated tripping device including a finger projecting into the path of sheets, means controlled by said tripping device for arresting the operation of said instrument, rollers engaging the sheet above and below the plane of feed and upon opposite sides of and adjacent to the tripping finger, and means for periodically raising and lowering the rollers which engage the sheet above the plane of feed. 90
17. The combination, in a paper feeding machine, of a sheet moving instrument, means for operating said instrument, a sheet actuated tripping device including a finger projecting into the path of sheets, means controlled by said tripping device for arresting the operation of said instrument, rollers engaging the sheet above and below the plane of feed and upon opposite sides of and adjacent to the tripping finger, and means for periodically raising and lowering the rollers which engage the sheet above the plane of feed. 95
18. The combination, in a paper feeding machine, of a sheet moving instrument, means for operating said instrument, a sheet actuated tripping device including a finger projecting into the path of sheets, means controlled by said tripping device for arresting the operation of said instrument, rollers engaging the sheet above and below the plane of feed and upon opposite sides of and adjacent to the tripping finger, and means for periodically raising and lowering the rollers which engage the sheet above the plane of feed. 100
19. The combination, in a paper feeding machine, of a sheet moving instrument, means for operating said instrument, a sheet actuated tripping device including a finger projecting into the path of sheets, means controlled by said tripping device for arresting the operation of said instrument, rollers engaging the sheet above and below the plane of feed and upon opposite sides of and adjacent to the tripping finger, and means for periodically raising and lowering the rollers which engage the sheet above the plane of feed. 105
20. The combination, in a paper feeding machine, of a sheet moving instrument, means for operating said instrument, a sheet actuated tripping device including a finger projecting into the path of sheets, means controlled by said tripping device for arresting the operation of said instrument, rollers engaging the sheet above and below the plane of feed and upon opposite sides of and adjacent to the tripping finger, and means for periodically raising and lowering the rollers which engage the sheet above the plane of feed. 110
21. The combination, in a paper feeding machine, of a sheet moving instrument, means for operating said instrument, a sheet actuated tripping device including a finger projecting into the path of sheets, means controlled by said tripping device for arresting the operation of said instrument, rollers engaging the sheet above and below the plane of feed and upon opposite sides of and adjacent to the tripping finger, and means for periodically raising and lowering the rollers which engage the sheet above the plane of feed. 115
22. The combination, in a paper feeding machine, of a sheet moving instrument, means for operating said instrument, a sheet actuated tripping device including a finger projecting into the path of sheets, means controlled by said tripping device for arresting the operation of said instrument, rollers engaging the sheet above and below the plane of feed and upon opposite sides of and adjacent to the tripping finger, and means for periodically raising and lowering the rollers which engage the sheet above the plane of feed. 120
23. The combination, in a paper feeding machine, of a sheet moving instrument, means for operating said instrument, a sheet actuated tripping device including a finger projecting into the path of sheets, means controlled by said tripping device for arresting the operation of said instrument, rollers engaging the sheet above and below the plane of feed and upon opposite sides of and adjacent to the tripping finger, and means for periodically raising and lowering the rollers which engage the sheet above the plane of feed. 125
24. The combination, in a paper feeding machine, of a sheet moving instrument, means for operating said instrument, a sheet actuated tripping device including a finger projecting into the path of sheets, means controlled by said tripping device for arresting the operation of said instrument, rollers engaging the sheet above and below the plane of feed and upon opposite sides of and adjacent to the tripping finger, and means for periodically raising and lowering the rollers which engage the sheet above the plane of feed. 130

machine, of a sheet moving instrument, means for operating said instrument, a sheet actuated tripping device including a finger projecting into the path of sheets, means controlled by said tripping device for arresting the operation of said instrument, rollers engaging the sheet above and below the plane of feed and upon opposite sides and adjacent to the tripping finger, and means actuated by the instrument arresting means for raising said rollers which engage the sheet above the plane of feed.

18. The combination, in a paper feeding machine, of a supporting arm or frame movable toward and away from a pile of sheets, and sheet moving means mounted upon said supporting arm or frame, means for moving said arm or frame in one direction, means for moving said arm or frame in the opposite direction, and a latching mechanism including a movable latch controlling member for retaining said arm or frame in one position, with a sheet controlled wedge constructed and arranged to move into engagement with said movable latch controlling member and thereby trip said latching mechanism.

19. In a paper feeding machine, the combination of a sheet moving device, and means for operating the sheet moving device, of a rock arm adapted to engage and elevate the sheet moving device, a spring mechanism tending to move said rock arm in one direction, mechanism adapted to periodically move the rock arm in the opposite direction, a latching bar connected with the rock arm, a latching arm engaging the latching bar and retaining the rock arm in one position with the spring mechanism under tension, a movable tripping member operatively connected with said latching arm and a sheet actuated wedging blade or plate adapted to move into engagement with and thereby actuate said movable member to release said latching arm and allow the spring mechanism to operate.

20. In a paper feeding machine, the combination of a sheet moving instrument, means for raising and lowering said instrument, a drop roller mechanism, a connection between said drop roller mechanism and said raising and lowering means arranged to cause the drop rollers to operate when said instrument is operating, and to be thrown out of operation when said instrument is raised out of operation, and a sheet actuated tripping device controlling said mechanism.

21. In a paper feeding machine, the combination of a sheet moving instrument, means for operating said instrument, means for raising and lowering said instrument with relation to the sheet support, a drop roller mechanism including a constantly driven under feed roller and a coöperating upper feed roller, a rock arm upon which said upper feed roller is mounted, and means connecting said rock arm with the instrument elevating means, said connecting means including a link connection between two of its parts.

22. In a paper feeding machine, the combination of a sheet moving instrument, a rock arm arranged to raise and lower said sheet moving instrument, means for operating said rock arm, a constantly running under feed roller, a drop roller coöperating therewith, a rock arm upon which said drop roller is journaled, and means connecting the drop roller rock arm with the instrument raising and lowering rock arm, said connecting means including a rock shaft and links having pivotal connections with said rock arms.

23. In a paper feeding machine, the combination of a sheet moving instrument, and a driving shaft operating said instrument, with a constantly rotating shaft geared to and driven by said instrument operating shaft, a roller mounted upon said constantly driven shaft, a coöperating roller mounted upon a rock arm in operative relation to said constantly driven roller, means for arresting the operation of said sheet moving instrument, latching means normally restraining said arresting means and including a latching arm suitably connected with the roller supported rock arm, and a sheet actuated wedging blade or plate adapted to be interposed between said coöperating rollers for actuating said latching means.

24. In a paper feeding machine, the combination of a sheet moving instrument, means for operating said instrument, means for arresting the operation of said instrument, a pivotally mounted sheet actuated tripping finger controlling said arresting means, a controlling rock arm having laterally projecting fingers extending upon opposite sides of and providing lost motion connection with the tripping finger, and a cam actuated mechanism suitably connected with said rock arm.
